DESIGN FOR A FRUIT JUICE SQUEEZER

Meyer Halperin, New York, N. Y.

Application September 11, 1935, Serial No. 58,514

Term of patent 14 years

To all whom it may concern:

Be it known that I, Meyer Halperin, a citizen of the United States, resident of Manhattan, in the county of New York and State of New York, have invented a new, original, and ornamental Design for a Fruit Juice Squeezer, of which the following is a specification, reference being had to the accompanying drawing, forming part thereof.

squeezer showing my design in its closed position, and

Figure 2 is a perspective view of the fruit juice squeezer showing my design in its opened position.

I claim:

The ornamental design for a fruit juice squeezer substantially as shown and described.

MEYER HALPERIN.
